UNITED STATES PATENT OFFICE.

CHARLES A. WAITZ, OF ROUSEVILLE, PENNSYLVANIA.

PUMP.

Application filed January 3, 1921. Serial No. 434,475.

To all whom it may concern:

Be it known that I, CHARLES A. WAITZ, a citizen of the United States, residing at Rouseville, in the county of Venango and

5 State of Pennsylvania, have invented new and useful Improvements in Pumps, of which the following is a specification.

It is desirable with pumps for oil wells to keep the working barrel free from sands 10 as they settle from the oils extending upwardly in the tubing. It is also desirable to protect the working barrel against damage either from the dropping of the tubing or where the tubing is let down too 15 rapidly and receives shock at the bottom of the well. The present invention provides a sand trap and protects the working barrel.

The invention is illustrated in the accompanying drawings as follows:—

20 Fig. 1 shows a central section of the pump embodying my invention.

Fig. 2 a section on the line 2—2 in Fig. 1.

1 marks the working barrel, and 2 the standing valve in the working barrel.

25 The working barrel is mounted on a pipe or standard 3 which extends upwardly for any distance that may be desired from a fitting 4. A strainer 5 is secured to the fitting 4 and a tubing 7 is connected with 30 the fitting 4 by a collar 6. The tubing is of larger size than the working barrel and extends upwardly to above the working barrel where it is connected by a coupling 8 with a fitting 9. The tubing 10 is secured 35 to the fitting 9.

The tube 7 is of sufficient size to provide for a space between the working barrel and the tube so that the sand settling from the tubing may pass through this space into 40 the space around the standard 3. This space may be given any capacity desired.

The pump plunger 11 operates in the working barrel and is of ordinary construction. A sucker rod 12 extends from the 45 plunger through a cap 13 which is mounted on the sucker rod and rests on the top of the working barrel thus preventing the settling of sand directly into the working bar-

rel. This cap is forced off the top of the working barrel by the up-flow of fluid to 50 permit the discharge of fluid from the working barrel to the tubing.

In order to center the working barrel I provide a spider 14 which is secured to the upper end of the working barrel in any 55 convenient manner as by threading the upper end of the working barrel and screwing it on to the working barrel. The spider has the projections forming the open spaces 15 through which the sand may pass.

The centering of the working barrel assists in the entry of the pump plunger when it has been removed and it is desired to return it to the working barrel.

What I claim as new is:—

1. In a pump, the combination of a working barrel; a tube larger than the working barrel within which the working barrel is placed, said tube extending below the working barrel and being of a size providing a 70 space between the barrel and the tube; a pipe smaller than the barrel extending downwardly from the bottom of the barrel and delivering oil to the barrel, the tube protecting the barrel, and the space within the tube 75 below the barrel forming a sand trap for sand settling past the barrel; and means for centering the barrel relatively to the tube.

2. In a pump, the combination of a working barrel; a tube larger than the working 80 barrel within which the working barrel is placed, said tube extending below the working barrel and being of a size providing a space between the barrel and the tube; a pipe smaller than the barrel extending downwardly from the bottom of the barrel and delivering oil to the barrel, the tube protecting the barrel and the space within the tube below the barrel forming a sand trap for sand settling past the barrel; and a spider 85 arranged on the barrel and engaging the walls of the tube for centering the barrel on the tube.

In testimony whereof I have hereunto set my hand.

CHARLES A. WAITZ.
